ATTORNEY.

UNITED STATES PATENT OFFICE

FREDERICK LA CROIX, OF AGAWAM, MASSACHUSETTS

PAPER-MAKING APPARATUS

Application filed November 28, 1930. Serial No. 498,620.

This invention relates to paper-making apparatus and is directed more particularly to coverings for dandy rolls and the like.

The principal object of the invention is the provision of a covering of novel form for dandy rolls and the like, whereby it is possible to produce new and novel watermarking effects.

In the detailed description of the invention hereinafter contained, the novel features will be described in connection with coverings for dandy rolls, which for convenience will be called web-marking elements, but it will be understood that the invention may be practised in connection with coverings for a cylinder of a paper-making machine or other making elements on which a web of paper may be formed.

Various novel features of the invention and the advantages thereof will be more fully hereinafter explained in connection with the accompanying drawing which shows the features of the invention in a general way and in the form at present preferred.

In the drawing:

Fig. 1 is a plan view of a portion of a marking element embodying the novel features of the invention.

Fig. 2 is a sectional view on the line 2—2 of Fig. 1, and

Figs. 3 and 4 are plan views of a portion of a paper sheet as it appears when marked by the marking element of the invention.

Referring now to the drawing in detail the invention will be more fully described.

In describing the invention reference will be made to a paper-making element, and there is shown in the drawing a section of a marking element or cover 2 for a dandy roll. Such a covering is known as a laid covering.

This covering comprises as shown a plurality of parallel bars 4 preferably of wire, which are secured together at intervals by transversely arranged wires 6. These wires are arranged in the well-known manner to interlock with the bars and hold them together and provide a unitary covering member.

In the ordinary practise these bars are of relatively stiff spring-like wire so that the

cover is more or less stiff and non-yieldable. According to this invention the bars 4 are made from bendable and relatively soft wire, such as soft drawn copper or the like, or the wires may be heat treated to make them soft and bendable.

It is common practise with such laid coverings to rotate the dandy roll so that it bears on the wet web of paper. The bars serve to displace or shift fibers in the web so that in the finished paper there appears a multiplicity of parallel dark and light lines alternately arranged. This is called a laid finish, and is one well known in the paper industry. The relatively dark and light lines are caused by relatively thick and thin portions of the paper.

Such a laid finish is monotonous and heretofore there has been no way of breaking the monotony except that in some cases patches of metal have been soldered on to the marking element. These when pressed by the element into the wet web of paper create a design or a marking corresponding to the shape of the marking element. The marking appearing of course, as a thinner portion of the paper, like any other watermark.

According to this invention it is desired to provide the paper with designs which are new in general appearance. This is accomplished according to the invention by identifying a design in the marking element formed by the bars. According to the preferred form of the invention I offset the bars transversely to the plane of the element.

To accomplish this I employ a design member in the form of the design it is desired to impart to the paper. This is placed on the marking element or the marking element may be placed on the design element. In either event the marking element is pressed into the bars so that the bars are offset as at 3 in Fig. 2 to conform to the shape of the design element.

In the case shown in Fig. 1 the design member is in the form of a crescent and may be a piece of metal cut to the shape desired. With the marking element placed thereover the element is pressed upon or struck with a rubber hammer, for instance, which forces

the bendable rods downwardly around the design element so that together the bars are offset to provide a depression conforming to the shape of the design element, which in this case is a crescent. Since the bars are relatively soft they are readily offset and the element has a depression on one side and a raised portion on the other.

Various designs may be used and in the manner described the bars may be offset so that they may be provided with depressions on one side of the element and raised portions on the other side corresponding to the shape of the design element. Of course a design or designs may be repeated as often as desired throughout a marking element.

With the marking element thus being offset with a design, the dandy roll covered with the element bears on a relatively wet paper web and shifts the fibers of the web so that the paper is marked not only to have the parallel light and dark streaks or lines, but will have the design of the depression associated therewith, as is indicated in Fig. 3, which shows a piece of paper wherein there appears light and dark lines 10 and 12 and a design 14.

If the element is placed on the dandy roll so that the design depressions are uppermost the web will show the design as being darker or thicker as in Fig. 3. If the element has raised portions uppermost the web will have the designs appearing as thinner or lighter with respect to the main body.

As stated marking elements for making laid paper have been formed from bars which are relatively stiff, such as hard drawn brass wires and the like and it is the intention that such bars produce light and dark streaks or lines which are substantially uniform in width and spacing to provide an effect which may be said to be symmetrical or regular.

The effects produced by my novel marking member may be such that the light and dark lines may be non-uniform in width and not in parallelism with one another. This non-uniform and non-parallel arrangement will have associated with it the design as in Fig. 4. Altogether there is produced a new and pleasing effect not possible by means of the prior art apparatus. This is accomplished by shifting or bending the bars out of parallelism as they are offset to produce the design depression and being bendable or relatively soft they bend readily. As shown in Fig. 4, the light and dark lines 16 and 18 are non-uniform and non-parallel and the design 20 is associated therewith.

Various designs of course may be employed and arranged as may be desired so that very many and beautiful effects may be created by means of the marking element which is provided with depressions by offsetting the bars of the element.

What I now desire to claim and secure by Letters Patent of the United States is:

1. A paper-marking element of the class described comprising in combination, a plurality of spaced rods of relatively soft annealed material secured together at spaced points throughout their length, adjacent rods being offset from the plane of the main body thereof in the form of a design to provide a depression and a raised portion on opposite sides of the element.

2. A paper-marking element of the class described comprising in combination, a plurality of spaced rods of relatively soft annealed material secured together at spaced points throughout their length, adjacent rods being offset from the plane of the main body thereof in the form of a design to form a depression and a raised portion on opposite sides thereof, the said rods being bent irregularly throughout their length so as to be non-parallel relative to one another, so as to form in wet paper contacted by the element a series of irregular, alternate light and dark non-parallel lines having a design superposed thereon.

In testimony whereof I affix my signature.

FREDERICK LA CROIX.
